**MOTOR PROTECTOR SWITCH OR SIMILAR
ARTICLE**

Burton O. Haun, Jr., and Walter H. Moksu, Attleboro, Mass., and Paul Wrablica, Jr., Corona, N.Y., assignors to Metals & Controls Corporation, Attleboro, Mass., a corporation of Massachusetts

Application August 18, 1958, Serial No. 52,253

Term of patent 14 years

(Cl. D26—13)

Fig. 1.

Fig. 2.

Fig. 3.

Fig. 1 is a top perspective view of a motor protector switch or similar article, showing our new design with the vertical ribs extending circumferentially;

Fig. 2 is a top plan view thereof; and

Fig. 3 is an elevational view thereof.

The dominant features of our new design are shown in solid lines in the drawing.

We claim:

The ornamental design for a motor protector switch or similar article, substantially as shown and described.
